[57] **CLAIM**

The ornamental design for a daybed for pets, as shown and described.

DESCRIPTION

FIG. 1 is a perspective view of a daybed for pets showing my new design, the broken lines are for purposes of illustration only and form no part of the claimed design;

FIG. 2 is a right side elevational view thereof, the left side is identical;

FIG. 3 is a front elevational view thereof, the rear being identical; and,

FIG. 4 is a top plan view thereof.

The bottom view is plain and unornamented.
